(57) **CLAIM**

The ornamental design for a protective glove with restrictive pads as shown and described.

DESCRIPTION

FIG. 1 is a perspective view of a protective glove with restrictive pads, showing the new design;
FIG. 2 is a front elevation view thereof;
FIG. 3 is a rear elevation view thereof;
FIG. 4 is a left side elevation view thereof;
FIG. 5 is a right side elevation view thereof;
FIG. 6 is a top plan view thereof; and,
The broken lines along the surface of the protective glove with restrictive pads depict claimed stitching.
